(57) CLAIM

The ornamental design for a pen cap, as shown and
described.

DESCRIPTION

FIG. 1 is a front elevation view of my design for a pen cap.
FIG. 2 is a side elevation view thereof.

FIG. 3 is a top view thereof; and,

FIG. 4 is a bottom view thereof.

The rear elevation view is the same as the front elevation
view.

The opposite side elevation view is the same as the side
shown.

The writing instrument depicted by means of broken lines in
FIGS. 1 and 2 has been shown for illustrative purposes only
and forms no part of the claimed design.

1 Claim, 1 Drawing Sheet
